UNITED STATES PATENT OFFICE.

WALTER G. SEABOLD, OF ALTON, ILLINOIS, ASSIGNOR TO ILLINOIS GLASS COMPANY,
OF ALTON, ILLINOIS, A CORPORATION OF ILLINOIS.

CARBOY-CASE.

1,343,340.

Specification of Letters Patent. Patented June 15, 1920.

Application filed November 1, 1919. Serial No. 335,128.

To all whom it may concern:

Be it known that I, WALTER G. SEABOLD, a citizen of the United States of America, and a resident of Alton, in the county of 5 Madison, State of Illinois, have invented certain new and useful Improvements in Carboy-Cases, of which the following is a full, clear, and exact description, reference being had to the accompanying drawings, 10 forming a part of this specification.

My invention relates to a carboy shipping or packing case composed of sections so united as to provide for one of the sections being pivotally mounted relative to the 15 other, to permit of a carboy in one of the sections being disposed in an elevated position and tilted to empty its contents. Briefly stated, the carboy case to which my present invention relates includes a carboy holding 20 section and a second section extensible relative to said carboy holding section, said sections being adapted to be drawn apart and pivoted to each other, so that the second section, when the case is in an inverted position, will constitute a support for the carboy 25 holding section which may then be tilted on its pivots in emptying the carboy.

Figure I is a side elevation of my carboy case.

30 Fig. II is a vertical section taken approximately on line II—II, Fig. I.

Fig. III is a horizontal section taken approximately on line III—III, Fig. I.

Fig. IV. is a side elevation of the carboy 35 case as it appears when in condition for tilting of the carboy.

Fig. V is a fragmentary vertical section on an enlarged scale illustrating one of the pivotal supports.

40 Fig. VI is a side elevation of the carboy case showing the sections in the positions assumed in assembling them.

In the accompanying drawings, A designates the main or carboy holding section of 45 my carboy case which may be of any suitable structure. Each of two opposite walls of said section has secured thereto, preferably midway of the top and bottom of the section, a headed pivot pin 1.

50 B designates a closure section, which, in the form of case shown, constitutes the top of my carboy case and may be of the form shown or of any other suitable form.

55 2 are extensions secured to the section B at the sides of the case occupied by the pivot

pin 1. When the carboy case is in closed condition, the extensions 2 extend downwardly along the sides of the carboy-holding section A, as seen in Figs. I to III, inclusive, but when the case is in condition 60 for tilting of a carboy in the section A, the closure section B is inverted, as seen in Fig. IV, and the extensions 2 serve as uprights in which the main or carboy-holding section A is pivotally supported, as will be herein- 65 after more fully explained.

Each of the extensions, 2 carried by the section B, is provided with a longitudinal slot 3, extending inwardly toward the section B from a point near the free end of the 70 extension. The slots 3 terminate at their inner end in enlargements 3' of sufficient size to permit the passage of the heads of the pins 1 through said extension, in order that the pins may occupy said slots. 75

The slots 3 terminate at such distances from the inner ends of the closure sections B as to permit of said closure sections being presented against one of the sides of the bottle-holding section A with the extensions 2 in horizontal positions, as seen in Fig. VI, and with the enlargement of the slots 3 opposite the headed pivot pins 1, so that said pins will pass through said enlargements to enter the slots 3. The extensions may therefore be quickly and readily secured to the pivot pins of the bottle-holding section or readily detached therefrom when the parts occupy the positions shown in Fig. VI, but when the sections of the 80 case are otherwise disposed relative to each other, there is no opportunity for the disconnection of the extensions of the closure section from the bottle-holding section. 85

Each extension 2 has secured to it near 90 its free end a suitable catch 4, preferably in the form of a spring tongue secured to a plate or boxing 5 attached to the extension. Said catch is preferably formed with a socket 6 adapted to receive the head of 100 one of the pivot pins 1, and with a finger 7 by which the catch may be drawn out of engagement with said pin.

In the practical use of my carboy case, the main or bottle-holding section A is utilized 105 during shipment and storage as the bottom section of the case, and the section B is utilized as a cover for the bottle-holding section to which it may be secured by any suitable form of fastener 8 carried in part 110

by each of the sections. By having one of the sections enter into the other section only one fastener is required.

To convert the case into a tiltable carboy 5 support the entire case, with the carboy therein, is inverted from the position in which it is shown in Figs. I and II, and the closure section B becomes a supporting section with the extensions 2 projecting upwardly therefrom. The bottle-holding section A is then raised between the extensions 2 until the pivot pins 1 carried thereby are elevated to the upper ends of the slots 3 and become seated upon the catches 4 secured to the extensions 2, which, by becoming positioned beneath the pivot pins 1, serve as bearings on which said pivot pins may turn. The main section A of the carboy case may be inverted either immediately after it has been disengaged from the inverted closure section or after it has been completely elevated as described, and in either instance the carboy-holding section will be so positioned as to dispose the neck 25 of the carboy uppermost.

The carboy-holding section, having been elevated and pivotally mounted as described, may be tilted at will and returned to upright position after each tilting operation, 30 and when the contents of the carboy have been emptied, the bottle-holding section may be readily returned to its former po-

sition by disengaging the catches 4 from the pivot pins 1 and returning the carboy sections to their original correlative positions. 35

I claim:

1. A carboy case comprising a pair of sections extensible relative to each other, one of said sections being provided with pivots 40 and the other section being provided with yieldable pivot receiving members for supporting said first-named section when the sections are drawn apart.

2. A carboy case comprising a pair of 45 sections extensible relative to each other, one of said sections being provided with pivots and the other section being provided with spring catches on which said pivots may turn when the sections are drawn apart. 50

3. A carboy case comprising a carboy-holding section provided with pivot members and a closure section having extensions provided with slots in which said pivot members may be moved to separate said 55 carboy-holding section from said closure section, and spring catches carried by said extensions whereby said pivot members may be supported when the sections are drawn apart. 60

In testimony that I claim the foregoing I hereunto affix my signature.

WALTER G. SEABOLD.
